Primary Examiner — Zenia Bennett(74) *Attorney, Agent, or Firm* — Plumsea Law Group, LLC(57) **CLAIM**

We claim the ornamental design for a toy figurine part, as shown and described.

DESCRIPTION

FIG. 1 is a top perspective view of a toy figurine part showing the new design;

FIG. 2 is a front elevational view of the toy figurine part of FIG. 1;

FIG. 3 is a rear elevational view of the toy figurine part of FIG. 1;

FIG. 4 is a right side elevational view of the toy figurine part of FIG. 1;

FIG. 5 is a left side elevational view of the toy figurine part of FIG. 1;

FIG. 6 is a top plan view of the toy figurine part of FIG. 1; and, FIG. 7 is a bottom plan view of the toy figurine part of FIG. 1. The broken lines and unshaded areas form no part of the claimed design.
